UNITED STATES PATENT OFFICE.

FRANK J. O'BRIEN, OF MILWAUKEE, WISCONSIN.

METAL-DRAWING APPARATUS.

1,341,664.

Specification of Letters Patent.

Patented June 1, 1920.

Application filed May 5, 1919. Serial No. 294,813.

To all whom it may concern:

Be it known that I, FRANK J. O'BRIEN, a citizen of the United States, residing at Milwaukee, in the county of Milwaukee and State of Wisconsin, have invented certain new and useful Improvements in Metal-Drawing Apparatus, of which the following is a specification.

This invention relates to improvements in metal drawing apparatus and has for its object to provide a new and improved apparatus especially adapted for use in cold drawing of pipe or the like to return the drawing member or carriage to the die member at the conclusion of the drawing operation.

These and other objects will be more fully explained and described in the following specification and shown in the accompanying drawings, in which—

Figure 1 is a side elevation of my apparatus;

Fig. 2 is a side elevation of the retrieving member; and

Fig. 3 is a vertical section through the retrieving member along the line 3—3 of Fig. 2.

Like numerals refer to like elements throughout the drawings, in which 10 designates generally the bench upon which is mounted a channel-shaped member 11 having the raised sides 11^a between which runs the endless chain 12. This chain runs over a pulley 13 at one end and a sprocket pulley 14 at the other end, the latter being actuated by a suitable shaft 14^a and driven gear 15.

Mounted upon the channel member 11 is what I term generally the carriage member 20 having suitable wheels or rollers 20^a, which ride upon the sides 11^a of the channel member 11, thereby reducing friction in the movement of the carriage member 20. The latter is of well known construction and needs no detailed description beyond the statement that at its forward end, as indicated at 20^b, is provided a plier portion which is utilized to grip the end base of the tube or metal A which is being drawn. This carriage member is further provided with a pivotally mounted hook 20^c, which may be dropped into engagement with the chain 12 when it is desired to start the drawing operation.

Located at one end of the channel member 11 is a die, generally indicated by the numeral 25, comprising a conventional form of

die, and where needed a mandrel, neither of which elements is shown since they *per se* do not form a part of this invention.

Mounted upon the die member 25 is a retrieving member, generally indicated by the numeral 30, provided with a base 30^a which is secured by cap screws 31, or the like, to the top of the die member 25. Extending upwardly from the base 30^a are the side plates 30^b in which is journaled the rotatable shaft 30^c, to which is secured the drum 30^d provided with a peripheral recess 30^e, upon which the cable 32 is wound. The drum is further provided with the shoulder 30^f, coaxing with a brake band 30^g, see Fig. 3 for example, which merely surrounds the shoulder 30^f, and which terminates at one end in the upstanding flange 30^g, and at the other end in an upstanding portion 30^h. An operating handle 34 is pivoted at 34^a to a cross-strap 35 and at its lower portion at 34^b to the upstanding portion 30^h of the brake band. The strap 35 extends through a guide or brace 36 which extends between brackets 40 and is secured thereto and is provided with a threaded portion 35^a which extends through the flange 30^g, being prevented from withdrawal by the adjustable nut 35^b. A coil spring 37 is located around the portion 35^a between the flange 30^g and guide 36. This construction, through the medium of the spring 37, normally maintains the brake band out of engagement with the shoulder 30^f. It will be seen that upon proper movement of the operating handle 34, the upstanding portion 30^h and the flange 30^g will be drawn toward each other against the action of the coil spring 37, and the brake band will be tightened upon the shoulder 30^f.

Adjacent the shoulder 30^f, the drum 30^b is provided with teeth 30^k with which contacts the pivoted bell crank 38, having the dog portion 38^a, said crank being rotatably mounted on a shaft 39 which extends between the brackets 40, projecting upwardly from and secured to the side plates 30^b. The bell crank 38 terminates in the weighted ball-shaped extremity 38^b, which serves to maintain the dog portion 38^a in engagement with the toothed periphery 30^k of the drum 30^d when in the position shown in Fig. 2, for example. This construction permits unwinding of the drum 30^d, but prevents its rewinding except when the bell crank 38 is thrown out of engagement. Each of the

side plates 30^b is recessed, as indicated by the numeral 30^m, and mounted in these recesses are the spiral springs 42, secured at one end to the peripheral wall of the recess 5 30^m and at their other ends to the hub 30^o of the drum 30^a, said hub being mounted upon and secured to the shaft 30^c. The construction and arrangement of these springs 42 are such that unwinding of the drum 30^a 10 would serve to compress or store energy in these springs. The cable 32 is secured at its free end to the front of the carriage member 20, as indicated by 20^e, Fig. 1.

In the operation of my apparatus, after 15 the end of the tube A or the like is reached and passed through the die it is seized by the plier portion 20^b of the carriage member 20, and the operator moves the hook 20^c into engagement with the endless moving chain 20 12, which draws the tube through the die 25 until the conclusion of the drawing operation, when the drawing member 20 is disengaged from the chain 12. The operator may then operate the brake lever 30 to hold the drum 25 30^a in position and then move the bell crank 38 out of engagement with the toothed portion 30^h of the drum. Thereafter, upon proper release of the brake lever 34, the stored energy of the springs 42 will rewind 30 the cable 32 upon the drum 30^a, thereby returning the carriage member 20 to the die member for a fresh drawing operation. The speed of this return movement may be regulated by proper actuation of the brake lever 35 34.

It will be obvious that my invention is susceptible of numerous modifications and improvements, and I do not wish to be restricted to the form shown except as defined 40 in the appended claims.

What I claim is:

1. In combination, a drawing member, a die carrying member, a retrieving member, said retrieving member comprising a drum, a flexible member carried on said drum and 45 attached to said drawing member, and spring means coacting with said drum to store energy during the movement of said drawing member away from said die carrying member and operably returning said 50 drawing member to said die member at the conclusion of said drawing movement.

2. In mechanism of the class described, a stationary die-carrying member, retrieving means mounted thereon and comprising a 55 reel, an actuating spring coacting therewith, and means to permit rotation of said reel in one direction and to prevent rotation in the other.

3. In mechanism of the class described, 60 a stationary die-carrying member, retrieving means mounted thereon and comprising a reel, an actuating spring coacting therewith, means to permit rotation of said reel in one direction and to prevent rotation in the 65 other, said last-named means comprising a pawl carried by said reel, and a pivoted coacting dog member.

4. In mechanism of the class described, a stationary die-carrying member, retrieving 70 means mounted thereon and comprising a reel, an actuating spring coacting therewith, means to permit rotation of said reel in one direction and to prevent rotation in the other, and manually operable brake mechanism coactable with said reel.

In testimony whereof I have subscribed my name.

FRANK J. O'BRIEN.
